RECORDING GALVANOMETER

Charles F. Wallace, Westfield, N. J., assignor to
 Wallace & Tiernan Products, Inc., Belleville,
 N. J., a corporation of New Jersey

Original application August 18, 1939, Serial No.
 290,842. Divided and this application November
 26, 1941, Serial No. 420,459

4 Claims. (Cl. 171—95)

This invention relates to electrical translating devices, i. e., devices which translate or convert electrical energy into mechanical movement. More specifically, the invention relates to translating devices of the class described in which the mechanical movement is utilized to produce indications which are a function of the supplied electrical energy, which indications may be temporary, or permanent.

Some of the objects of the invention are to provide devices of the class described which are comparatively rugged, simple in construction and inexpensive to manufacture; yet quite sensitive and accurate.

Other objects and advantages will appear as the invention is hereinafter disclosed.

Referring to the drawing which illustrates what I now consider to be a preferred physical embodiment of the invention, I have there shown, diagrammatically in some respects, and with parts broken away for clarity in illustration, an instrument embodying the various features of my invention.

The instrument shown comprises a stator 105 which is shown in the form of a spool having a central slot or rotor-receiving opening extending axially of the spool. A rotor or armature 106 is shown mounted for partial rotation or oscillation, in the stator opening, about a geometric axis which passes through the rotor and is at right angles to the axis of the spool 105 and intersects the last mentioned axis at, or substantially at, a point midway of the ends of the spool.

The axle 111, which supports the rotor 106 for oscillation about its geometric axis, is preferably offset as shown so as to lie outside the spool 105 and yet permit of the desired oscillation of the rotor 106 within its limits of travel. While the axle 111 may be supported at one of its ends for rotation or oscillation, it is preferably provided with two ends, on opposite sides of the offset portion of the axle, and each of the axle ends is suitably journaled in a corresponding one of two bearings presently to be described in greater detail. The opposite end portions of the axle 111 are co-axial with the geometric axis of oscillation of the rotor 106.

While the rotor or armature 106 may assume other forms and be made of other materials, it is shown in the shape of a circular disc of a magnetic alloy such as that known as "Alnico." These alloys are considerably lighter in weight than other materials, such as cobalt-magnet steel, of which such armatures may be constructed, and the "Alnico" type of alloys provide

greater magnetic retentivity, i. e., greater resistance to demagnetization, and are comparatively resistant to corrosion. However, these "Alnico" alloys, having the stated desirable properties, are comparatively brittle and practically impossible to work by machining operations other than grinding operations.

In my device, the axle 111, being offset as shown and above described, does not pass through the rotor or disc 106, but the latter is imperforate and is suitably secured to the offset portion of the axle 111 as by soldering the disc 106 to the axle at a point 126 on the periphery of the disc. Thus while the geometric axis of oscillation of the disc rotor 106 passes through the disc at its center, the axle 111 does not actually pass through the disc 106 at all; the disc being, as stated, imperforate.

By providing the construction shown, the desired alloy may be employed for the rotor 106; thereby providing a rotor which is comparatively light in weight, has high magnetic retentivity, and which may be manufactured and assembled with facility and inexpensively.

The stator or spool 105 is provided with a substantially helical multi-layer winding 107 of suitably insulated copper or other electrically conductive wire, the ends of which are electrically connected to electrical terminals 108 and 109 secured to a terminal strip 110, of insulating material, which is riveted or otherwise suitably secured to one of the ends of the spool 105.

While the geometric axis about which the rotor 106 oscillates, passes through the stator winding 107, the axle 111, being offset as shown and described, does not pass through the winding 107. Therefore, the construction described has additional advantages with respect to the construction of the deflection-producing winding and the efficiency of operation of the instrument.

If the axle 111, instead of being offset, actually passed through the stator, it would be necessary to provide an offset stator winding, or two spaced stator windings, or otherwise to provide a clearance opening in the winding, for the axle 111. By virtue of the construction shown and described, it is possible to employ a single long winding, as shown, having a better space factor, i. e., one producing a greater magnetic flux for a given cross-sectional area, as there is more wire and less insulation or other voids in the construction.

Preferably, the spool 105 is made of copper so as to constitute, in effect, a low resistance short

circuited winding providing a desired damping of undesired oscillations of the rotor 106.

The stator 105 is shown suitably secured to bars 119, in turn suitably secured to the panel 103 of the instrument.

A front bearing plate 115 is shown secured to the panel by means of studs 117, and a rear bearing plate 118 is shown secured to the bars 119.

The axle 111 may be made of steel and its opposite ends are preferably conical as shown at 114 and journaled in the small ball bearings 112 and 113. The bearings 112 and 113 are carried by the front and rear bearing plates 115 and 118, respectively. Either or both of these bearings may be mounted so as to be adjustable in the direction of the geometric axis of the axle 111 and rotor 106. Thus, the front bearing 112 has its race externally threaded to cooperate with internal threads in the bearing plate 115; a lock nut 116 being provided to retain the bearing in any desired position to which it has been axially adjusted. The rear bearing 113 may be made similarly adjustable and settable.

In the particular instrument shown, the shaft or axle 111 has secured to one of its end portions a recording arm 122 carrying a marking pen or stylus 125 which traces a record upon the record sheet 102. While the record sheet 102 may be otherwise shaped and otherwise actuated, it is shown in the form of a circular sheet rotated by a suitably timed motor 101, such as a spring motor or clock-works, mounted on the rear of the panel 103 and having a drive shaft extending therethrough; the sheet 102 being suitably secured to the said drive shaft at its front end.

A spiral spring 120 having one of its ends secured to the axle 111 and its opposite end secured to an arm 121, in turn secured to the bearing plate 118, may be provided for biasing the rotor 106 and the indicating or recording arm 122. The magnitude of the biasing torque provided by the spring 120 may selectively be varied by setting the arm 121, which is angularly adjustable on the bearing plate 118.

An arm 124, secured to the axle 111 so as to be angularly adjustable thereon, as by means of a set screw, is provided with a weight 123 for counter-balancing the arm 122 and the pen or stylus 125. If desired, the arm 124 and its weight 123 may additionally be employed as a substitute for the biasing spring 120, or, supplemental to the spring 120, for providing the desired biasing torque for the rotor 106. To these ends, the weight 123 may be radially adjusted on the arm 124 as by the screw and slot adjustment shown, which, acting in conjunction with the angular adjustment of the arm 124, provides for either counter-balancing or biasing the structure carried by the shaft 111.

The disc rotor or armature 106 constitutes a permanent magnet. It is so permanently magnetized as to have a north pole at its periphery and a south pole also on the periphery and diametrically opposite the north pole. By so locating the permanent north and south poles in relation to the winding 107 that the lines of magnetic flux or force parallel the plane of the winding 107, when the latter is deenergized, maximum deflecting torque and a substantially uniform deflection of the pen arm 122 will be attained when the winding 107 is energized. If it is desired to spread the readings at one or the other end of the movement of the arm 122, the permanent magnet 106 may be so mounted angularly with respect to the arm 122 as to obtain an

exponential relationship between the energization of the winding 107 and the deflection of the arm 122, which relationship may be substantially a function of the tangent of the angle of deflection. In any event, the deflection of the arm 122 from normal position, i. e., its position when the winding 107 is deenergized, will be dependent upon the magnitude of the direct current passing through the winding 107.

The instrument shown and described may therefore be employed as a galvanometer or other electrical indicating instrument.

This application is a division of my co-pending application Serial No. 290,842, filed August 18, 1939, for Methods and systems of apparatus for detecting and controlling changes in composition of liquids.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted, without interfering with the more general results outlined, and the invention extends to such use within the scope of the appended claims.

What I claim is:

1. An electrical translating device comprising in combination, an imperforate armature of magnetic material, means mounting said armature for angular movement about a geometric axis passing through said armature, and electromagnetic means for angularly deflecting said armature, said mounting means comprising an axle extending along said axis and having an offset portion secured to an outer edge of said armature to maintain said armature within said electromagnetic means, and means pivotally mounting said axle exteriorly at opposite sides of said electromagnetic means, said armature comprising a separate, permanently magnetized member of high magnetic retentivity secured at an edge thereof to the offset portion of the axle and magnetically polarized in a direction at an angle to said geometric axis, and said mounting means being adapted to maintain the armature normally in a position with its magnetic flux in angular relationship to that produced by the electromagnetic means.

2. In an electrical translating device, in combination, an imperforate disc of magnetic material, mounting means therefor including an axle having an offset portion connected to said disc at its periphery and whose geometric axis of rotation passes through the disc substantially centrally of the latter, and electromagnetic means for angularly deflecting said armature, said disc being permanently magnetized with a diametrical polarization and said mounting means being adapted to maintain the disc normally in a position with its magnetic flux in angular relationship to that produced by the electromagnetic means.

3. An electrical indicating instrument comprising in combination, a deflecting coil, an imperforate armature of magnetic material extending into said coil and substantially surrounded thereby, and mounting means for the armature including an axle wholly outside said coil supporting said armature for oscillation about a geo-

metric axis passing through said coil and through said armature, said axle having an offset portion extending around said coil and connected to the periphery of said armature, said armature being magnetically polarized in a direction at an angle to said geometric axis, and said mounting means being adapted to maintain the armature normally in a position with its magnetic flux in angular relationship to that produced by the deflecting coil.

4. An electrical indicating instrument comprising in combination, a spool of electrically conductive nonmagnetic material, a helical deflecting winding on said spool, an imperforate disc armature of magnetic material extending into

the opening in said spool, and means including an axle having an offset portion connected to the periphery of said disc for supporting said disc for angular movement about a geometric axis passing through the center of said disc and through said spool substantially midway of the ends of the latter, said armature consisting of a separate, permanently magnetized disc of high magnetic retentivity, diametrically polarized, and said supporting means being adapted to maintain the disc normally in a position with its magnetic flux in angular relationship to that produced by the helical deflecting winding.

CHARLES F. WALLACE.
